(57) **CLAIM**

The ornamental design for a hanging bag storage device, as shown and described.

DESCRIPTION

FIG. 1 is a front top side perspective view of a hanging bag storage device, showing my new design;

FIG. 2 is a front side elevation view thereof;

FIG. 3 is a rear side elevation view thereof;

FIG. 4 is a left side elevation view thereof;

FIG. 5 is a right side elevation view thereof;

FIG. 6 is a top side plan view thereof; and,

FIG. 7 is a bottom side plan view thereof.
